GRINDING, POLISHING, AND FEATHER-
EDGING TOOL

Carm P. Rhees, Staten Island, N. Y.

Application September 19, 1949, Serial No. 116,438

3 Claims. (Cl. 51—197)

1

This invention relates to a grinding, polishing and feather-edging tool.

Portable, motor-driven grinding, polishing and feather-edging tools and attachments are well known in many industries, including the motor vehicle body building and repairing industry. These tools and attachments are available in many forms and types. The kind of tool to which the present invention applies makes use of relatively large grinding, polishing and feather-edging discs which are removably and replaceably mounted thereon. It is generally used in motor vehicle body repair work, as, for example, where a suitable metallic compound is applied for fill-in purposes, or where torn body parts are welded together, or where touch-up work is done.

One of the important requirements of this type of tool, especially for polishing and feather-edging operations, is that there be sufficient slippage between the polishing or feather-edging disc and the carrier on which it is mounted.

Another important requirement of this type of tool is that it be provided with suitable fastening means for holding the grinding, polishing and feather-edging discs thereon for the full useful life of said discs.

Still another important requirement is that each disc be individually mountable and demountable with respect to the tool for as many times as may be necessary to derive the fullest use and benefit therefrom in accordance with conventional shop practices. A given disc, for example, may be used rather sparingly on any one occasion, and it is important that said disc be removable from the tool and replaceable thereon as many times as may be necessary during the course of its normal life span.

The prior art discloses no grinding, polishing and feather-edging tool of this general character wherein all of the requirements above mentioned, as well as other requirements, are fully met. In some cases, the fault lies with the tool itself; in most cases, the fault lies with the type of grinding, polishing or feather-edging disc used. The fastening means whereby the discs are fastened to the tool either provide for no slippage of the discs whatsoever or for excessive slippage. The discs themselves are much too weak in the area of their engagement with the fastening means so that distortions and tears frequently take place long before the full useful life of the discs is expended. Although the discs are designed for mounting on the tool and removing therefrom as many times as may be necessary, frequently a single use thereof is sufficient to preclude and prevent any further use thereof.

It is accordingly the principal object of this invention to provide a grinding, polishing and feather-edging tool of the character described

2

which meets all of the requirements for efficient and satisfactory use above set forth. More specifically, it is the principal object of this invention to provide a suitable disc-fastening means on the tool and a suitable disc-attachment for cooperation therewith. The disc-fastening means of the present invention allows the disc to slip to the very extent desired while at the same time it securely holds the disc on the tool without damage or injury to that part of the disc which it engages. The disc is provided with a reinforcing member or attachment in said area of its engagement with the disc-fastening means so that the danger of damage or injury to the disc in that area is still further lessened or removed. And finally, the disc-fastening means and the disc reinforcing member are so designed that the disc may be securely mounted upon said fastening means by simply snapping it on said fastening means, and it may very readily be removed therefrom by simply snapping it off said fastening means.

More specifically, the disc-fastening means of the present invention comprises a button-shaped member which has a disc-engaging head and a reduced neck which carries the disc, and a tension member which presses the disc against said disc-engaging head. The strength of the tension member determines the frictional coefficient between the disc and the disc-engaging head of the button-shaped member. It will hereinafter be seen, however, that this tension member is not the only means which controls slippage of the disc. The disc-reinforcing attachment of the present invention comprises at least one and preferably two relatively small ring-shaped reinforcements which are placed on both sides of the disc, one of them between the operative side of the disc and the disc-engaging head, and the other between the inoperative side of the disc and the tension member. These reinforcements may be secured to the disc or they may merely be juxtaposed to the disc. Preferably, however, at least one of the reinforcing rings should be fastened to the disc and that is the ring which is on the inoperative side of the disc. Each reinforcing ring is made of relatively stiff material but its inner edge is weakened in some way, as by means of notches, to render it sufficiently flexible to slip over the button-shaped member of the disc-fastening means, either to mount the disc thereon or to remove it therefrom.

A preferred form of this invention is shown in the accompanying drawing, in which:

55 Fig. 1 is an exploded, perspective view of a tool incorporating the features of the present invention.

Fig. 2 is an enlarged diametrical section through the operating head of the tool, showing 60 all of the parts thereof in assembled condition,

including the disc, its two reinforcing rings, the button-shaped disc holder on which said disc and its reinforcing rings are mounted, and the tension member which holds said disc and said reinforcing rings tight against said button-shaped disc holder.

Fig. 3 is a fragmentary face view of one of said discs and disc reinforcing rings, shown mounted upon a button-shaped disc holder made in accordance with the present invention.

Fig. 4 is a face view or plan view of one of the reinforcing rings.

Fig. 5 is an edge view of a sand or emery paper disc, showing a reinforcing member secured to its back or inoperative side.

Fig. 6 shows two such discs fastened back to back with one of said reinforcing rings mounted between them.

Fig. 7 is another edge view of a polishing or buffing disc or attachment, showing a reinforcing member secured to its back or inoperative side.

Fig. 1 shows a motor driven tool 10 to which the present invention may be applied. It has a drive shaft 11 and a molded rubber pad 12 or any other suitable pad of resilient or non-resilient material. It will be seen in Fig. 2 that the drive shaft or spindle 11 is provided with external screw threads and that pad 12 is provided with a tapped hole 13 to receive said threaded shaft. Thus far the construction is conventional.

Disc-holding member 15 is a tubular member which is provided with internal screw threads 16. It is adapted to be mounted upon threaded shaft 11 in screw-threaded engagement therewith as Fig. 2 clearly shows. It accommodates a socket type of set screw or plug 17 which abuts the end of the drive shaft to lock the disc-holding member in place thereon. This arrangement is also conventional.

Disc holder 15 has an annular bead or lip 20 formed thereon, peripherally thereof, at its forward or leading end. Behind said annular bead, which is, or may be described as, of button shape, is a reduced neck portion 21. Behind the neck portion 21 is an annular flange 22 which extends radially outwardly from the main body of said tubular disc holder 15. Behind flange 22 is a reduced end portion 23 which extends to the very back end of said tubular disc holder.

Pad 12 has an annular recess 25 which is adapted to accommodate end portion 23 of the disc holder when both the disc holder and said pad are securely mounted on the drive shaft of said motor driven tool 10. The pad also has another annular recess 26 which is relatively shallow and which surrounds its first-mentioned recess 25. The dimensions of recess 25 and end portion 23 are such that there is a relatively snug fit between the pad and said end portion 23 of the disc holder and the depth of recess 26 is such as to prevent flange 22 of the disc holder from engaging the face of the pad.

The tool is provided with a second pad or backing 30 which rests against the face of molded pad 12. Pad or backing 30 comprises a fiber disc 31 and a cushion 32 secured thereto which is made of felt or other suitable material. The fiber back 31 has a hole 32 formed therein, centrally thereof, and the diameter of said hole is but slightly larger than the diameter of end portion 23 of the disc holder. It is possible, therefore, to mount said fiber back 31 on end portion 23 as Fig. 2 clearly shows. A centrally extending hole 34 is formed in cushion 32 which is considerably larger in diameter than hole 33 in the

fiber back and also considerably larger in diameter than flange 22 of the disc holding member 15. It is, therefore, possible to mount pad or backing 30 upon the disc holder in such manner that back 31 occupies a position between flange 22 on the one hand and the face of molded pad 12 on the other hand. A certain amount of tension may be incorporated into fiber back 31 by simply tightening the disc holder 15 upon the drive shaft 11. This has the effect of pushing or drawing the center of back 31 into the shallow annular recess 26 which is formed in the face of molded pad 12.

Molded pad 12 functions in the manner of a back support with respect to backing or pad 30. Said backing or pad 30 functions in the manner of a backing or support for disc 35 which is shown in Figs. 1, 2, 3 and 5. It may also serve as a backing for double disc 36 shown in Fig. 6 as well as for disc or attachment 37 shown in Fig. 7. The frictional engagement between these discs and backing 30 as well as the action of the tension member above mentioned, determine the extent of slippage of the discs, controlled, of course, by the pressure applied to the work.

Disc 35 is known as a feather edging disc. It comprises a paper disc 40 coated on its face with emery dust or granules 41 and provided with a centrally disposed hole 42. As Fig. 2 shows, this hole 42 corresponds in diameter to neck 21 of the disc holder, and hence its diameter is somewhat smaller than the diameter of button-shaped end portion or bead 20 of said disc holder. It is necessary, therefore, that the inner edge of the disc immediately surrounding its central hole yield sufficiently to enable the disc to pass over the button-shaped end portion 20 in either direction.

As appears from Fig. 5, a reinforcing ring 45 may be mounted on the back or inoperative side of the disc. In the preferred form of this invention, the reinforcing ring is secured to the back of the disc by means of a suitable cement or other suitable fastening means. This reinforcing ring is made of relatively stiff material, such as pressed fiberboard, and it has a centrally situated hole 46 formed therein, the diameter of said hole corresponding to the diameter of hole 42 in disc 35, and also corresponding to the diameter of neck 21 of the disc holder. Notches 47 are formed in and along the inner edge of reinforcing ring 45 to provide said inner edge with a certain amount of flexibility. It is this flexibility which enables the reinforcing ring to pass over the button-shaped end portion 20 of the disc holder. It is desirable to use two reinforcing rings for each disc, one being situated at the back of the disc and the other being situated in front of the disc. Both reinforcing members may be secured to the disc, or only one of them, or neither of them. Preferably, however, at least one reinforcing member is secured to the disc and that is the one which is situated at the back of the disc. See Fig. 5. Fig. 1 shows neither of the two reinforcing members affixed to the disc.

A tension member 50 may be mounted on neck portion 21 of the disc holder. This tension member which, preferably, is a coiled compression spring bears at its back end against flange 22 of the disc holder and its forward end against the reinforcing ring 45 which is secured to the back of the disc. Spring action is thereby developed which causes the face of the disc to press firmly against the reinforcing ring which is situ-

ated in the front of said disc and it also causes said front reinforcing ring to press tightly against the button-shaped forward end of the disc holder. A frictional coefficient is thereby achieved which assists in preventing slippage of the disc relative to the disc holder. When the disc is pressed against the work, additional friction is generated between the back of the disc and the face of the backing or pad 30 to further reduce the possibility of slippage of the disc. Some slippage will take place, however, when the disc is pressed firmly or tightly against the work, but such slippage is both desirable and necessary, especially for feather edging. When such slippage takes place, the front reinforcing ring prevents the emery of the disc from wearing away the button-shaped forward end of the disc holder.

The grinding disc shown in Fig. 6 differs from the feather edging disc shown in Fig. 5 in that it comprises a double disc with a reinforcing ring in the middle. Disc 36 comprises two emery discs 52 and 53, respectively, which are disposed back to back, with a reinforcing ring between them. They may be secured to the reinforcing ring by means of cement or any other suitable fastening means. Since the emery side of one of the discs 52 and 53 bears against the padding or cushion 32 of backing 30, and the emery side of the other of said discs bears against the work, considerable friction will be generated both between the first-mentioned disc and the cushion, and between the second-mentioned disc and the work, before any slippage of said discs relative to the disc holder will take place. In the preferred use of grinding disc 36, three reinforcing rings should be used, the reinforcing ring which is secured between the two discs 52 and 53, one reinforcing ring on the emery side of disc 52, and another reinforcing ring on the emery side of disc 53.

The polishing or buffing disc shown in Fig. 7 includes a backing 55 which may be made of pressed fiberboard, and a buffing pad 56 which may be made of any suitable buffing material. If desired, disc 37 may be made of sheepskin, the skin or leather thereof constituting backing 55 and the hair, pile or fur thereof constituting the padding 56. A reinforcing ring may be attached to the back of disc 37 and another ring may, if desired, be placed in front of said disc.

The foregoing is descriptive of a preferred form of this invention, and it will clearly be understood that other forms of the invention and modifications of the instant form may readily be had within the broad scope and coverage of the invention. For example, if the paper or other material of which the discs are made, is sufficiently strong, there will be no need to apply a reinforcing ring thereto. In such case, the inner edge of the disc should be sufficiently inflexible so as to render it necessary to use force to snap it over the button and yet sufficiently flexible so that it can be snapped over the button without great difficulty. Hence, notches similar to the notches formed in the reinforcing ring should be formed in the disc to give its inner edge that required flexibility and resilience for which the present invention calls.

The notched inner edge of the reinforcing member merely illustrates an inner edge which is sufficiently yielding and resilient for the purposes of the present invention. Notches are generally required in relatively stiff material such as fibre board, but it would not be necessary to provide

notches in somewhat more elastic material, such as synthetic rubber or textile fabric. Hence when elastic materials are used either in the disc itself or in the reinforcing ring, there will be no need to notch their respective inner edges to provide the resilience which they already have. Broadly speaking, therefore, any disc which is provided with a snap-on feature or facilities which would enable it to snap over the button-shaped disc holder, would meet the requirements of the present invention and come within its scope. This is true whether the disc has or has not a reinforcing ring, and whether the disc or its reinforcing ring is or is not notched, and whether, if notched, the notches are similar or not similar to the notches shown in the drawing.

The invention is also sufficiently broad to encompass a button-shaped disc holder wherein the button comprises an annular flange which is continuous a full 360° (as shown in the drawing) as well as an interrupted flange or a plurality of disc or disc reinforcement engaging bosses or projections.

Having thus described my invention, what I claim as new and desire to secure by Letters Patent, is:

1. A feather-edging, grinding and polishing tool of the character described, having a disc holder and a disc removably mounted on said disc holder, said disc holder having an enlarged annular end portion, a reduced neck behind said end portion which carries the disc—said reduced neck being circular in cross section—to provide a yielding frictional drive between said disc holder and said disc, and an annular flange behind said neck portion, a compression spring being provided between the flange and the disc to press said disc against the enlarged end portion.

2. A feather-edging, grinding and polishing tool in accordance with claim 1, wherein a reinforcing ring is disposed on the disc between said disc and the spring and wherein a second reinforcing ring is disposed on the disc between said disc and the enlarged end portion of the disc holder.

3. A feather-edging, grinding and polishing tool of the character described, having a disc holder and a disc removably mounted on said disc holder, said disc holder having an enlarged annular end portion, a reduced neck behind said end portion which carries the disc, and an annular flange behind said neck portion, a compression spring being provided between the flange and the disc to press said disc against the enlarged end portion, a fibre backing plate behind said annular flange, a cushion disc secured to the front of said backing plate, said cushion disc having an axial opening therethrough, the diameter of which is considerably larger than the diameter of said flange.
